UNITED STATES PATENT OFFICE.

ARTHUR C. HUNT, OF GREENVILLE, SOUTH CAROLINA.

DIRIGIBLE HEADLIGHT.

1,100,737.

Specification of Letters Patent. Patented June 23, 1914.

Application filed May 6, 1913. Serial No. 765,851.

To all whom it may concern:

Be it known that I, ARTHUR C. HUNT, citizen of the United States, residing at Greenville, in the county of Greenville and State of South Carolina, have invented certain new and useful Improvements in Dirigible Headlights, of which the following is a specification:

This invention relates to improvements in dirigible locomotive head-lights, and the primary object of the invention is to provide automatic means whereby the light rays of the head-light may be shifted according to the curvature of the track upon which the locomotive is traveling, thus materially reducing the accidents occurring through inefficient light service, and facilitating to a great extent the operation of the train line, since greater speed may be maintained without danger of accidents, by directing the light rays straight ahead of the locomotive at all times.

A further object of the invention is to provide means operated by bodily lateral movement of the locomotive to shift the head-light and cause the light rays generated thereby to follow or shift according to the direction of travel of the locomotive, such movement of the head-light directing the light rays along the curved track and not tangent thereto as heretofore.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an elevation of the means employed for shifting the head-light, the supporting beams of the locomotive and the rails being shown in section; Fig. 2 is a section on line 2—2 of Fig. 1; Fig. 3 is a section on line 3—3 of Fig. 1; Fig. 4 is a section on line 4—4 of Fig. 2; and Fig. 5 is a front elevation of the carriage employed in connection with the present invention, a portion thereof being shown in section, as well as a portion of the locomotive body.

Referring now to the drawings, wherein

is illustrated the preferred form of my invention, the numeral 1 designates the two parallel supporting beams of the locomotive terminating at their forward extremity a cross beam 2 from which the fender depends. Vertically extending supports 3 are bolted to the beams 1 as at 4, the said beams 3 terminating at their lower extremity in a head 5 formed integrally therewith to which a boxing 6 is bolted as at 7 for effecting a support or journal for the forward axle of the locomotive. The said axle 8 is loosely journaled within suitable blocks 9 supported by the boxing 6 through the medium of a cushion 10 in the form of a spring interposed between the lower extremity of the head 5 and the said block 9, the weight of the locomotive retaining the block within the boxing 6. A carriage, designated in its entirety by 11, provides a journal for the axle 8 of the locomotive, the said carriage having a sleeve 12 arranged over a portion 13 of the axle smaller in diameter than the main portion 8 thereof, the shoulders formed by the said smaller portion preventing lateral movement of the carriage upon the axle. Extensions 14 extend vertically of the carriage through an opening 15 within a cross beam 16, the latter being secured at each end to the vertically extending beams or supports 3. A rack bar 17 is formed integrally with and at the upper extremity of the extensions 14, the said rack bar extending from one to the other of the extensions as is clearly shown in Fig. 5 of the drawings, the teeth thereof meshing with a segmental rack 18 keyed or otherwise secured to a vertically extending head-light support or rod 19 pivotally mounted upon a plate or laterally projecting flange 20 formed integrally with the cross beam 16. The head-light 21 of the locomotive is secured to the upper extremity of the rod 19 and is rotatably mounted upon a suitable bracket or plate 22 secured to the locomotive as is shown by the dotted lines in Fig. 1, the rotation of the light base being facilitated through the medium of bearing-balls 23 or rollers interposed between the said base and the plate or bracket 22.

Having described the detail construction of the head-light operating means, it now remains to fully set forth the operation of the device. The forward axle 8 of the locomotive being loosely or slidably journaled within the blocks 9 carried by the depending

or vertical supports 3, it will be seen that lateral movement of the forward end of the locomotive is provided during the travel of the locomotive over a curved section of track, such movement causing the segment 18 carried thereby to bodily move laterally with respect to the stationary rack 17 into which it meshes thereby causing the said segment to partially rotate for imparting a like movement to the lamp supporting rod 19. As the lamp supporting rod 19 is partially turned or shifted and a like movement is imparted to the head-light 21 causing the light rays generated thereby to follow the curvature of the track and not extend tangent thereto as heretofore.

It will be seen from the above, taken in connection with the accompanying drawings that lateral movement of the cross beam 16 caused by a like movement on the part of the forward end of the locomotive will impart bodily lateral, as well as rotary movement to the segmental rack 18; that movement of the said rack 18 will in turn partially rotate the head-light 20, the rotation of the latter being governed according to the curvature of the track over which the locomotive is traveling; and that by providing a slot 15 of greater length than the width 30 of the carriage extensions 14, movement of the beam 16 is limited.

In reduction to practice, I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various 35 minor changes in the details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. In combination with a locomotive, a relatively movable head light, a bodily movable support carried by the front axle of the locomotive, and a movable carriage mounted upon said axle, and means upon said carriage adapted to engage means upon said support to shift the said light through 55 movement of the support, as and for the purpose set forth.

2. In combination with a locomotive, a movable head-light, a bodily and laterally movable support carried by the front axle 60 of the locomotive, an immovable carriage mounted upon the said axle, and means including a rack bar mounted upon the said

carriage adapted to engage means upon said support to shift the said light according to the lateral movement of the latter. 6

3. In combination with a locomotive, a movable head-light, a laterally and bodily movable support mounted upon the front axle of the locomotive, an immovable carriage carried by the said axle, a rack bar mounted upon the said carriage, a segmental rack meshing into the said rack bar and means connecting the said segmental rack to the said head-light for shifting the latter according to the movement of the said support. 65

4. In combination with a locomotive, a movable head-light, a laterally and bodily movable support mounted upon the front axle of the locomotive, an immovable carriage carried by the said axle, a lamp support carried by the said laterally movable support, a segmental rack secured to the said lamp supporting means and a rack bar mounted upon the said carriage adapted to 75 engage the said segmental rack for shifting the said light according to the lateral movement of the said support. 70

5. In combination with a locomotive, a movable head-light, a laterally movable support carried by the front axle of the locomotive, an immovable carriage carried by the said axle, means connecting the said light to the said movable support, a segmental rack carried by the said light supporting means and a rack bar mounted upon the said carriage adapted to engage the said segmental rack for shifting the said light according to the lateral movement of the 85 said support. 80

6. In combination with a locomotive, a bodily and laterally movable support, a stationary carriage, said carriage adapted to extend through an opening formed in said support, said opening forming a means 90 whereby lateral movement of said support is limited, a stationary rack bar upon said carriage, a vertical rod journaled at one end within said support, said rod being bodily movable therewith, a segment mounted upon said rod, said segment being disposed for engagement with said rack and a lamp rotatable with said rod, the bodily lateral movement of said support adapted to actuate said segment by reason of its engagement with 105 said rack to partially rotate said lamp, as and for the purpose set forth. 100

In testimony whereof I affix my signature in presence of two witnesses.

ARTHUR C. HUNT.
